TWEEZER

Samuel Segal, New York, N. Y.

Application December 2, 1931, Serial No. 578,525

20 Claims. (Cl. 128—354)

The present invention relates to gripping and extracting instruments, and, although not limited thereto, it particularly relates to small manually actuated instruments utilized for the personal toilet and usually designated as tweezers.

Among the objects of the present invention are to provide devices, or instruments of the character described which may be conveniently manipulated by the hand without danger of pinching the flesh; which include few constituent parts and are susceptible to inexpensive manufacture and easy assembly; and which without injury thereto may be readily dismantled, quickly repaired and easily reassembled.

In one embodiment, the gripping and extracting device or tweezer instrument of the present invention includes a pair of elongated jaws, one end of which may be flattened and/or corrugated to form gripping faces, and the other ends of which are so provided with correlated recesses, projections and shoulders and positioned inside of a cylindrical guide that an effective pivotal connection is formed therebetween. Symmetrically attached to the sides of the jaws by pivoted links, and in slots in the cylindrical guide by elongated recessed knobs, are a pair of wings to be gripped by the hand in actuating the device. Within the cylindrical guide is positioned a spring having a retainer, which retainer fits in the recesses of the elongated knobs and locks them in position.

In the accompanying drawing in which there is shown one of the various possible embodiments:

Fig. 1 shows a side view partly in section of the expanded device.

Fig. 2 shows a side view of the device when collapsed.

Fig. 3 is a transverse section upon the line 3—3 of Fig. 1.

Fig. 4 is a transverse section upon the line 4—4 of Fig. 2; and

Fig. 5 shows the inside faces of the pivotal ends of the tweezer jaws.

Fig. 6 illustrates three views of an upper portion of the side wings of the tweezer.

The tweezer instrument, as shown, is provided with a pair of elongated semi-cylindrical jaws 10 and 11, one end of which terminate in gripping faces 12 and 13, preferably corrugated and projecting beyond the recessed portions 14 and 15.

The other end of the jaws is retained inside of the sleeve or guide 16 and the contacting faces are so constructed as to form a pivotal connection therebetween. In forming this pivotal connection the jaw 10 (see also Fig. 5) is provided with a channel 17 to receive the elongated boss 22 of the jaw 11. The sides 18 of the channel 17

project beyond the face 50 to form a shoulder 19 which cooperates with the shoulder 20 formed by the depression 21 above the face 51. The bottom face 25 of the cylindrical end 23 of the jaw 11 forms a stop for the sloping upper end 24 of the jaw 10.

The upper end of the sleeve 16 is closed as indicated at 48, and is provided with an integral knob 49 having a central opening or bore 50. Retained in the sleeve 16 between the cylinder 26 and the cylindrical end portion 23 of the jaw 11 is a coil spring 27 for normally pressing the jaws forwardly and keeping the instrument in expanded position as shown in Fig. 1.

The upper end of the sleeve 16 is squared at 28, and is provided with two symmetrical transverse channels or grooves 29, which serve as fulcrums for and receive the elongated inward projections 30 of the wings 31. The projections 30 are centrally recessed at 32. The recesses 32 partly encircle the spring retainer or cylinder 26. The retainer 26 locks the wings 31 in position in the grooves 29 and prevents transverse slippage of the projections 30 from the squared portion 28 of the sleeve 16. The overhanging lips 25 or edges 33 of the grooves 29 cooperate with the transversely disposed grooves 34 on the upper portion of the projections 30 whereby the upper portions of the arms or wings 31 are retained in the grooves or sockets 29 and lateral slippage 30 of the projections 30 is prevented.

The outer faces of the wings 31 are desirably embellished or decorated, as is also the outside of the guide 16, and the lower outer portions 35 of said wings are suitably flattened and ridged to 35 form finger grips in any suitable manner.

The inner faces of the wings 31 and the outer faces of the jaws 10 and 11 are provided with ears 36 and 37 respectively, in which (see also Fig. 4) are press-fitted the pivot pins 38, the ends 39 of which are of reduced diameter and receive the sides of the U-shaped channel links 40, the channel portion facing downwardly and forwardly. The upper face 41 of the link 40 upon collapsing of the instrument is stopped by 40 the extension 42 of the ear 36 (see Fig. 2). In expanded position the extension 47 of the links 40 will be stopped by the ears 37 as shown in Fig. 1. In assembly the sides of the channel link 40 may be pressed into the reduced ends 39 of the pivot pins 38.

Both in the expanded position of Fig. 1 and contracted position of Fig. 2 there is no possibility of injuring by pinching the hand or flesh in operating the tweezer. Heretofore the link members were reversed and had their channels facing upwardly and rearwardly. The gap portions now shown at 47 in Fig. 2 formerly appeared between the link 40 and the thumb portion 35 of the wings 31. With the tweezer col- 60 55 50 45 40 35 30 25 20 15 10 5 55 60

lapsed the edges of the gap formed a miniature tweezer which tended to catch the flesh of the user. It has been found by reversing and inverting the channel links to face downwardly and forwardly the gap at 47 upon collapsing of the instrument is transferred to a position where no injury can ensue.

To dismantle the instrument as shown in Fig. 1, a wire (not shown) is inserted in the bore 50 to press down the locking means or cylinder 26 below the grooves 29, whereupon the projections 30 of the wings 31 may be slipped out of the grooves 29. Subsequently the wings 31 with the linked jaws 10 and 11 may then be removed from 15 the cylindrical guide 16, as may also the spring 27 and its retainer 26.

Initial reassembly is accomplished by inserting the retainer 26 and the spring 27 in the cylindrical guide 16 placing the jaws 10 and 11 20 together so that the ridge 22 will fit into the channel 17 and the shoulders 19 and 20 will contact with each other. Then the retainer 26 should be pressed downwardly by a pin or rod through the opening 50 to depress the cylindrical retainer 26 against the energy of spring 27 25 and bring it below the elevation of the sockets 29. The retainer is held at this elevation whereupon the upper portions of the wings may be brought upwardly and readily slipped into the 30 sockets 29. Upon the removal of the rod (not shown) from the opening 50, the retainer 26 releases due to expansion of spring 27 and enters between the curved faces 32 of the flanges 33 and thus pivotally locks the upper portions of 35 the arms 31.

In operation the wings 31 may be gripped at 35 between the fingers, preferably the thumb and the index finger of the right or left hand at substantially any angle. Upon compression, the first movement will bring the gripping portions 40 and 13 of the jaws 10 and 11 together and the next movement will result in a compression of the spring 27 with an extracting movement of the jaws 10 and 11. In practice the gripping and extracting operations follow rapidly, one after the other, the fingers continuing the collapsing movement until the link 40 is stopped by the projection 42.

In the construction shown, the wings 41 of 50 the cylindrical guide 16 and the jaws 10 and 11 may be preferably die castings while the links 40 may be made of sheet metal, bent and cut to form rectangular channel members. By utilizing die castings it is possible to form more 55 accurate extracting gripping faces 12 and 13 on the jaws 10 and 11, which in closed position should admit of the passage of a fine thread of light when held up to a source of illumination. The pivot pins 38 may be readily press-fitted 60 into holes provided in the ears 36 and 37. It will be noted that the construction is altogether free of rivets and transverse springs.

As many changes could be made in the above construction, and many apparently widely different embodiments of this invention could be devised without departing from the scope thereof, it is intended that all matter contained in the above description or shown in the accompanying drawing shall be interpreted as illustrative 70 and not in a limiting sense.

I claim:

1. In a device of the character described, a guide, a pair of jaws sliding within said guide, a pair of wings linked to said jaws and having 75 pivotal connections with said guide, and slideable

means within said guide to lock said connections in position.

2. The device of claim 1 in which the guide takes the form of a hollow cylinder with an externally squared end, in which and transverse channels are provided on opposite sides thereof, and the squared end being of such size and shape and the channels being of such depth that their central portions will open into the inside of the cylinder, the locking means taking form of a cylindrical slide in said cylinder passing through the portions of said wings disposed in said channels.

3. The device of claim 1 in which said pivotal connections include elongated knob-shaped projections, in which the guides are provided with channels to receive said projections and in which the guide encloses a cylindrical locking means, said projections being recessed to receive said locking means.

4. In a device of the character described, a guide, a pair of jaws sliding within said guide, a pair of wings having pivotal connections with said guide, and links connecting said wings to said jaws, said links being formed of U-shaped channel members, the open portions of which face forwardly.

5. A tweezer including a pair of side wings, a pair of jaws, a tube within which the inner ends of said jaws extend having transverse external channels adjacent its closed end, a cylindrical plug within said tube, the end edges of said wings extending transversely to the bodies thereof, fitting in said channels and recessed to encircle the side faces of said plug.

6. A tweezer including a pair of jaws movable into gripping position, a guide for said jaws, means for actuating said jaws to initially establish such position and subsequently move the same bodily rearwardly, resilient means enclosed in said guide for automatically reestablishing said jaws to non-cooperating position upon said last-named means being released and projecting stops on said actuating means and said jaws and slideable means disposed within said guide and urged by said resilient means to lock said actuating means.

7. In a device of the character described, a guide, a pair of jaws sliding within said guide, a pair of wings linked to said jaws and having pivotal connections with said guide, and means within said guide to lock said connections in position, said guide being longitudinally provided with an opening to permit of insertion of a tool to move said locking means and unlock said connections.

8. In a device of the character described, a guide, a pair of jaws sliding within said guide, and a pair of wings linked to said jaws and having pivotal connections with said guide, the contacting faces of said pair of jaws being provided at one end with gripping faces and at the other end with cooperating bosses and depressions fitting into each other to form a pivotal connection.

9. A tweezer including a pair of side wings, a pair of jaws, a tube within which the inner ends of said jaws extend having transverse external channels adjacent its closed end, a cylindrical plug within said tube, the end edges of said wings extending transversely to the bodies thereof, fitting in said channels and recessed to encircle the side faces of said plug, the closed end of said tube being provided with an open-

ing to permit of insertion of a tool to move said plug and unlock said wings.

10. In a tweezer, the combination of, a hollow guide having opposed sockets adjacent its upper end, a pair of jaws having their upper portions removably and pivotally associated and arranged within said guide, said jaws having their lower portions extending beyond said guide and including cooperating gripping and extracting faces, wings having flanges pivotally and removably disposed in said sockets, link means pivotally connected to said jaws and wings, a member within said guide for removably locking said flanges, and a spring within the guide for normally holding said faces apart and said member in locking relation with said flanges.

11. In a tweezer, the combination of, a hollow guide having opposed sockets adjacent its upper end, a pair of jaws comprising a pivotal connection, said connection including a boss extending from one of said jaws, the other jaw of said pair having a recess for receiving said boss, said jaws having their upper portions movably disposed in said guide, wings having flanges pivotally mounted in said sockets, link means pivotally connected to said jaws and wings, a member within the guide for removably locking said flanges, and a spring within the guide for normally holding the lower portions of said jaws apart and said member in locking relation with said flanges.

12. In a tweezer, the combination of, a guide having opposed sockets, a pair of gripping jaws having their inner portions slidably disposed in said guide, a pair of wings including flanges removably and pivotally mounted in said sockets, links pivotally connected to said jaws and wings, means disposed within said guide for removably locking said flanges and means for normally holding gripping faces of said jaws apart.

13. In a tweezer, the combination of, a hollow guide having opposed sockets adjacent its upper end, a pair of jaws having their upper portions removably and pivotally associated and disposed in said guide, said jaws having their lower portions extending beyond said guide and including cooperating gripping and extracting faces, means for reciprocating said jaws relative to said guide and means within the latter for removably holding upper corresponding portions of said reciprocating means within said sockets and for normally holding said faces apart.

14. In a tweezer, the combination of, a guide having opposed sockets, a pair of gripping jaws having their upper ends inserted in said guide, a pair of wings having projections pivotally arranged in said sockets, links pivotally connected to said jaws and wings, said jaws having their

lower ends provided with gripping faces, the upper ends of said jaws having a pivotal connection comprising bosses and depressions fitting into each other, displaceable means within the guide for removably locking said projections and spring means within the guide for holding said displaceable means in locking relation and said faces normally apart.

15. In a tweezer, the combination of, a guide, a pair of jaws their upper ends slidably disposed within said guide, a pair of wings linked to said jaws and having pivotal connections with said guide, spring means within said guide to normally hold the lower portions of said jaws apart and slidable means within said guide 15 acted upon by said spring means to removably lock said connections.

16. The tweezer according to claim 15 characterized in that one of said jaws is provided with an extension contacting with said spring 20 means.

17. The tweezer according to claim 15 in which the jaws and wings are provided respectively with ears substantially removed from the ends thereof having protuberances on which 25 said links are pivotally connected, said links having substantially U shaped channel sections partly embracing said ears, the open portion of said U shaped sections facing forwardly.

18. The tweezer according to claim 15 in which said guide is a cylindrical tube having opposed sockets in communication with the bore of said tube, said sockets forming a complementary part of said pivotal connections which include elongated knob shaped projections extending from said wings and receivable in said sockets.

19. The tweezer according to claim 15 characterized further in that the slidable means is cylindrical and said guide is a cylindrical tube 40 having opposed sockets in communication with the bore of said tube, said sockets forming a complementary part of said pivotal connections which include knob shaped projections extending from said wings and receivable in said 45 sockets, said projections being recessed to receive said slidable means for removably locking said projections.

20. In a tweezer, the combination of, a guide, a pair of jaws having their upper ends slidably 50 within said guide, a pair of wings having pivotal connections with said guide, link means pivotally connected to said jaws and wings, a coiled spring to normally hold the lower portions of said jaws apart and stop means extending inwardly from said wings and cooperating with said links to limit the retraction of said jaws upon the manipulation of said wings.

SAMUEL SEGAL.
